(57) **CLAIM**

The ornamental design for a funnel for replenishing an automated pharmacy machine, as shown and described.

DESCRIPTION

FIG. 1 is a top, front perspective view of a funnel for replenishing an automated pharmacy machine showing our design; FIG. 2 is a side view thereof;

FIG. 3 is an opposing side view thereof;

FIG. 4 is a top view thereof;

FIG. 5 is a bottom view thereof;

FIG. 6 is a front view thereof; and,

FIG. 7 is a rear view thereof.

In the drawings, the broken lines in FIGS. 1, 4, 5, and 7 depict portions of the design that form no part of the claim.

1 Claim, 6 Drawing Sheets
